[57] **CLAIM**

The ornamental design of a caterpillar spring ride, as shown.

DESCRIPTION

FIG. 1 is a side elevational view of a caterpillar spring ride in accord with my new design, the opposite side elevational view being the mirror image thereof, and in the drawings the spring shown in phantom lines is not a part of the design, FIG. 2 is a front elevational view of the playground caterpillar spring ride,

FIG. 3 is a rear elevational view; and,

FIG. 4 is a top plan view of my new design.
